FOLD-DOWN GATES

Harold E. Hastings, Denver, Colo.

Application March 4, 1957, Serial No. 643,745

2 Claims. (Cl. 39—24)

This invention relates to an automatic, self-opening and self-closing gate, and has for its principal object the provision of a highly efficient gate which will swing forwardly and downwardly from the path of an approaching vehicle and then return to the closed position after the vehicle has passed, and to so construct the gate that the possibility of damage to either the gate or the vehicle will be reduced to a minimum.

Another object is to provide a shock absorber or bumper for a gate of the swing-down type which will cushion the impact of the vehicle thereagainst, and which will function as a guard or shield to prevent undercarriage parts of the vehicle from striking the gate as the vehicle passes thereover.

A further object is to provide return springs for returning the gate to the closed position which will be easy and economical to install, and which will be elevated above normal snow levels and protected against dust, grit, ice, etc. which might interfere with the operation of the gate.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a face view of the improved gate in the closed position;

Fig. 2 is a cross-section through the gate, taken on the line 2—2, Fig. 1;

Fig. 3 is an enlarged, vertical section, taken on the line 3—3, Fig. 1;

Fig. 4 is a fragmentary, detail section, taken on the line 4—4, Fig. 3; and

Fig. 5 is a still further enlarged, detail section, taken on the line 5—5, Fig. 1.

In the drawing, the improved gate is illustrated mounted between two gate posts 10 and 11 supporting any conventional type of fence 12.

The improved gate comprises two vertical gate stiles 13 separated by parallel, spaced-apart, horizontal gate bars 14, 15, and 16. The stiles are formed with transversely extending and axially aligned foot portions 17 welded or otherwise fixedly secured thereto. The foot portions 17 rest upon bearing plates 18 and are secured in place thereon by means of U-shaped, staple-like straps 19. The straps 19 extend through openings in the base plates and may be driven into the ground or into a sill 39 extending across the gate opening in alignment with the road surface. The foot portions 17 are rotatable in the straps 19 so that the gate may be tilted downwardly from the vertical position in either direction to a horizontal position on the roadway.

The gate is resiliently maintained in the vertical position by means of torsion springs 20. Each of the torsion

2

springs is mounted in a cylindrical spring barrel 21 extending horizontally through one of the posts 10 or 11. A spring shaft 22 extends axially through each of the spring barrels 21 and projects inwardly through a head 23 on the barrel toward the gate. The securing between the spring and the shaft and the barrel may be made in any desired manner so that the spring will be wound by rotating the shaft in one direction, and so that the spring will rotate the shaft in the opposite direction when the shaft is released.

As illustrated, one extremity of each spring is passed through an opening 40 in the shaft, the other extremity is fitted into a receiving notch 41 in the outer edge of the barrel. The latter extremity of the barrel is closed by means of a suitable cap 24. The caps are locked against rotation on the barrels by means of suitable set screws 42, and the barrels are prevented from rotation in the posts 10 and 11 by means of bracket straps 25 which are secured to the posts and to the caps 24 by means of suitable attachment screws 26. Thus, it can be seen that if the spring shaft 22 at the post 10 be rotated in a counter-clockwise direction, the springs 20 will be wound to store energy.

A winding sheave 29 is fixedly mounted or keyed on the inner extremity of each shaft 22 in any desired manner. A flexible cable 30 is secured at its extremity to the sheave 29 at the post 10, such as by means of a terminal screw 27, and is wound about the sheave. A similar cable 31 is similarly secured and wound about the sheave 29 at the post 11.

The cables 30 and 31 are secured to the improved gate in any desired manner so that when the gate is swung in either direction, the cables will rotate the respective spring shafts 22 counter-clockwise to wind the springs 20, and when the gate is released, the stored energy in the wound springs will rotate the sheaves 29 in a clockwise direction to rewind the cables 30 and 31 and restore the gate to its vertical position.

The gate is provided with two vertical, resilient bumper plates 32 and 33 which are secured to the gate by a pair of links 34 rotatably mounted on the gate bar 15, and a corresponding pair of links 35 are rotatably mounted on the lower gate bar 16 parallel to the links 34. The two bumper plates 32 and 33 are turned inwardly at their lower extremities so that they will contact each other to limit the downward movement of the bumper plates.

The parallel links 34 and 35 extend upwardly and outwardly from the bars 15 and 16 so that when pressure is applied to either bumper plate, the latter can move inwardly and upwardly toward the gate. The parallel links 34 and 35 are prevented from longitudinal movement on their respective bars by means of set collars 36.

Any suitable spring arrangement could be used to resist the upward and inward movement of the parallel links 34 and 35 to provide a cushioning effect for the bumper plates 32 and 33. As illustrated, this cushioning effect is accomplished by extending the two cables 30 and 31 into the opposite extremities of the middle gate bar 15, thence extending the cable 30 upwardly to a connection 37 on the bumper plate 33, and by similarly extending the cable 31 upwardly and outwardly to a connection 38 on the bumper plate 32. This arrangement employs the resiliency of the springs 20, both to provide a cushioning effect for the bumper plates 32 and 33 and to resiliently return the gate to the closed position.

It is believed the action of the improved gate will be apparent from the above description. Briefly, when an automotive vehicle approaches the gate, the front bumper of the vehicle will strike one of the bumper plates 33, forcing it inwardly and upwardly against the resistance of the springs 20. The forward movement of the vehicle will then cause the gate to tilt forwardly and downwardly

with the engaged bumper plate providing a smooth, continuous surface over which the undercarriage of the vehicle frictionally travels. When the vehicle leaves the engaged bumper plate, the gate will be immediately swung upwardly to its former vertical closed position by the reaction of the wound springs 20.

If found necessary, a trench 28 may be formed at each side of the mid-portion of the gate to receive the lower-most bumper plate when the gate is depressed.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. In a gate of the swing-down type having two spaced-apart fence posts with a gate frame positioned between said posts and having hinge means hinging said gate at its bottom so that it may swing from a vertical position between said posts to a horizontal position at either side thereon, means for resiliently supporting said gate frame in the vertical position comprising: spring means; a spring barrel horizontally and fixedly mounted in each of said posts above said hinge means, the axes of said barrels lying substantially in the plane of said gate frame; a spring shaft extending axially through each of said barrels and projecting therefrom inwardly toward said gate frame; a torsion spring surrounding the spring shaft in each barrel, one extremity of each spring being connected to the barrel and the other extremity of each spring being connected to the spring shaft so that rotation

5 of said shafts will impart a rotative bias to said springs; a cable sheave mounted on the inner extremity of each spring shaft between the gate frame and the adjacent post; and a flexible cable secured at its one extremity to each cable sheave and being wound thereabout, said cables being secured at their other extremities to said gate frame at the sides thereof at a point below said cable sheaves and above said hinge means, said cables being wound about said sheaves in a direction which will increase the torsion in said springs as said gate is swung downwardly in either direction.

10 2. Means for resiliently supporting a gate of the swing-down type as described in claim 1 having a substantially vertical bumper bar positioned medially at each face of said gate; parallel links hinged to and extending between the gate and each bumper bar at an angle from the horizontal so that said bumper bars will move vertically if forced toward said gate; and means for connecting said other extremities of said cables to said bumper bars so that said torsion springs will serve the double purpose of resiliently resisting vertical movement of said bumper bars and also resiliently resisting tilting of said gate in either direction.
